Fig. 10.

FIGURE 1 is an isometric view of the upper side of one form of my paving block design;

FIGURE 2 is an isometric view of the lower side of the paving block as shown in FIGURE 1;

FIGURE 3 is a lower left side elevational view of the block as shown in FIGURE 1;

FIGURE 4 is a lower right side elevational view of the block as shown in FIGURE 1;

FIGURE 5 is an upper right side elevational view of the block as shown in FIGURE 1;

FIGURE 6 is an isometric view of the upper side of another form of paving block design;

FIGURE 7 is an isometric view of the lower side of the paving block as shown in FIGURE 6;

FIGURE 8 is a lower left side elevational view of the block as shown in FIGURE 6;

FIGURE 9 is a lower right side elevational view of the block as shown in FIGURE 6; and

FIGURE 10 is an upper right side elevational view of the block as shown in FIGURE 6.

I claim:

The ornamental design of a paving block, substantially as shown and described.
